ABSTRACT: Flocking material is conveyed from a supply container to a portable electrostatic applicator through a flexible tube in which is reciprocated an elongated flexible impeller. The impeller includes a series of semispherical propelling elements mounted on a longitudinally extending flexible rod.

Patented Aug. 3, 1971

FLEXIBLE TUBE CONVEYOR

BACKGROUND OF THE INVENTION

In applying flocking material such as short lengths of nylon fibers to a prepared surface coated with adhesive, as for example, a vertical wall surface, it is common to employ a portable applicator which has a chamber for receiving a small quantity of flocking fibers. Flexible lead wires connect the applicator to a high voltage power supply to produce an electrostatic charge on the fibers. The charge causes the fibers to be discharged toward the surface in a substantially parallel pattern so that the ends of the fibers adhere to the adhesive surface thereby producing a flocking which has maximum density and a nap thickness substantially the same as the length of the fibers. After the supply of fibers in the applicator chamber is exhausted, it is necessary to interrupt the flocking operation and refill the chamber with another supply of fibers.

Frequently, the operator of the applicator is standing on a ladder or scaffold and it is necessary for him to step down from the scaffold each time the hopper requires refilling. Thus it has been found that during the flocking of a large area, there is considerable time required just for the refilling operations. Furthermore, during each refilling operation, the adhesive continues to dry or set with the result that progressively fewer fibers adhere to the surface thereby producing a flocking of nonuniform density. Moreover, the extra weight added to the portable applicator by the hopper or container defining the chamber causes considerable strain on the operator's arm supporting the applicator.

SUMMARY OF THE INVENTION

The present invention is directed to a flexible tube conveyor which is ideally suited for progressively delivering flocking material from a supply container to a portable electrostatic applying gun or device. It is to be understood, however, that the conveyor of the invention is not limited to handling only flocking fibers, but may also be used for transporting other solid materials, as for example, granular or powdered material. As a primary feature, the present invention provides a conveyor for progressively transporting a material from a supply source or container to a portable applicator or discharge device whereby it is unnecessary to interrupt the application or discharge of the material at periodic intervals.

In accordance with a preferred embodiment of the invention, a conveyor includes a flexible tube of circular cross section and formed by spirally winding a semirigid interfitting plastic extrusion so that the inner surface of the tube has a spiral slot or groove forming generally radial surfaces. An elongated flexible impeller extends within the tube and includes a series of semispherical propelling elements each having an annular radial surface facing in the desired direction of flow of material through the tube. The propelling elements are connected by an elongated flexible plastic rod which extends through the center of each element.

One end of the flexible tube is secured to a hopper or container which receives a supply of material to be conveyed, and the other end of the tube is attached to a portable applicator or discharge device. One end portion of the impeller extends through the supply container and is connected to a power-operated reciprocating drive, and the other end of the impeller is attached to a tension spring within the discharge device. In accordance with another embodiment, the impeller is reciprocated by intermittently energizing one or more annular coils mounted on the tube surrounding corresponding magnetic elements forming part of the impeller.

BRIEF DESCRIPTION OF THE DRAWING

FIG. 1 is a somewhat schematic elevational view, in part section, of flocking apparatus including a conveyor constructed in accordance with the invention;

FIG. 2 is a fragmentary view in part axial section of the conveyor shown in FIG. 1;

FIG. 3 is an enlarged fragmentary section of the conveyor tube shown in FIGS. 1 and 2;

FIG. 4 is a radial section taken generally on the line 4-4 of FIG. 2; and

FIG. 5 is a fragmentary section similar to FIG. 2 of a conveyor constructed in accordance with another embodiment of the invention

DESCRIPTION OF THE PREFERRED EMBODIMENTS

FIG. 1 shows flocking apparatus which is constructed in accordance with the invention and which generally includes a portable base 10 supporting a hopperlike container 12 adapted to receive a supply of flocking material M, as for example, nylon fibers each having a length of approximately one-eighth inch. A cover 13 is mounted on the container 12 for maintaining the humidity of the flocking material M substantially constant.

In accordance with the present invention, a flexible tube conveyor 15 includes a flexible semirigid tube 16 formed by spirally winding an extruded interfitting plastic element having a cross-sectional configuration defined by a U-shaped portion 17 (FIG. 3) integrally connected to a tongue portion 18. One manufacturer of the tube 16 is Dayco Corp. located in Dayton, Ohio. The inner fitting connection of the portions 17 and 18 of the tube 16 as it is spirally wound provides for substantial flexibility of the tube and also defines a spiral slot or groove 19 within the inner and outer surfaces of the tube 16.

The inlet end of the tube 16 is connected by a fitting 21 to the container 12 so that the inlet is concentric with a circular opening 22 formed within the container adjacent the bottom wall. The outlet or discharge end of the tube 16 is connected to a portable electrostatic applying device or gun 25 which is connected by lead wires 26 to a high voltage power supply (not shown).

An elongated flexible impeller 30 extends within the tube 16 and includes a series of longitudinally spaced semispherical elements 32 preferably formed of a rigid plastic material. Each element 32 includes a flat radially extending annular surface 33 which faces toward the applying gun 25 and adjoins a semispherical surface 34. The outer diameter of each element 32 is slightly smaller than the inside diameter of the tube 16 to define an annular passage 35 (FIG. 4) when the elements 32 are concentric with the tube 16.

An elongated rod 36, preferably formed of a flexible plastic material such as nylon, extends through the center of each element 32. One end of the rod 36 extends through the lower portion of the container 12, through a bearing 37 and is connected to a rod 38 slidably mounted within a bearing 39 secured to the base 10. A variable speed motor 40 is also mounted on the base 10, and a circular drive plate 41 is mounted on the output shaft of the motor. An arm 42 has one end pivotally connected to the rod 38 and an opposite end eccentrically connected to the plate 41 by a pin shaft 43 extending into one of a series of holes 44 within the plate 41. The holes 44 are located at different radial distances from the axis of the motor shaft to provide for selectively changing the amplitude of the reciprocating movement of the rod 38 and the impeller 30. The opposite end of the impeller rod 36 is connected to a tension spring 45 which is located in the applying gun 25.

A number of the impeller elements 32 are mounted on the rod 36 so that the lower portion of the container 12 is reciprocated at a predetermined speed, as for example, 2,000 cycles per minute, the flocking material M flows into the inlet of the conveyor tube 16 and is rapidly advanced by the elements 32 in a step-by-step manner through the tube 16 to the applying gun 25. When the flocking fibers are exposed to the electrostatic charge, they are oriented in a substantially parallel pattern, and the ends of the fibers are attracted to the adhesive-coated surface S thereby forming a thick dense nap having a thickness substantially equal to the length of the fibers.

While the drive for the impeller 30 may be constructed to provide a return stroke which is faster than the forward or feed stroke, it has been found that the simple harmonic motion provided by the eccentric drive plate 41 provides a sufficient flow of flocking material M through the tube 16 to the applying gun 25. Of course, the drive motor 40 may be controlled by a switch conveniently located on the applying gun 25 so that the flow of flocking material through the tube 16 can be controlled according to the rate at which the material is applied.

Referring to FIG. 5, in place of the eccentric or harmonic drive provided by the motor 40, the plate 41 and the arm 42, it is within the scope of the invention for the conveyor 15 to include one or more annular solenoid coils 50 which are mounted on the tube 16 at longitudinally spaced intervals. The armature for each coil 50 is formed by a pair of impeller elements 32' constructed of steel or other magnetic material instead of a plastic material. A return tension spring 51 is connected to one end of the impeller rod 36', and a smaller tension spring 52 is connected to the opposite end of the rod 36' to maintain the impeller 30 taut. When the coil 50 is energized, the impeller 30' is momentarily advanced to the right, and when the coil 50 is deenergized, the spring 51 returns the impeller 30' to its normal or home position (FIG. 5). Thus by intermittently energizing the coil 50, the impeller 30 is reciprocated within the tube 16.

From the drawing and the above description, it is apparent that a flexible tube conveyor constructed in accordance with the invention provides desirable features and advantages. For example, the combination of the flexible tube 16 and the flexible impeller 30 provides a positive means for transporting a solid material from a supply container to a portable dispensing or applying device. As mentioned above, while the conveyor 15 is ideally suited for transporting flocking fibers since there is no airflow which causes uncontrolled discharge of the fibers, it is within the scope of the invention to employ the conveyor for transporting other materials, as for example, for transporting powdered or granular materials.

The cooperation between the impeller elements 32 and the inner surface of the tube 16 assures that the material is positively advanced in a step-by-step manner. That is, the annular flat surfaces 33 of the impeller elements 32 are effective to advance the material within the tube 16, and the generally radial surfaces defined by the spiral groove 19 within the inner surface of the tube 16 resist the movement of the material with the sloping or semispherical surfaces 34 of the elements 32 when the impeller 30 is retracted. It is to be understood that the impeller 30 would normally rest on the inner surface of the tube 16 and would not be precisely concentric as theoretically shown in FIGS. 2 and 4.

While the forms of apparatus herein described constitute

preferred embodiments of the invention, it is to be understood that the invention is not limited to these precise forms of apparatus, and that changes may be made therein without departing from the scope and spirit of the invention. For example, an elongated flexible impeller might be constructed in the form of a flexible tube similar to the tube 16, with an outer surface formed by a series of longitudinally spaced frustoconical surfaces.

What I claim is:

10. 1. An improved conveyor for transporting material, comprising an elongated flexible tube of circular cross section and having an inlet end and a discharge end, an elongated flexible impeller of circular cross section and extending within said tube and cooperating with the inner surface of said tube to define an annular passageway therebetween, said impeller including means for advancing material in said passageway in a step-by-step manner in response to reciprocating movement of said impeller, and power-operated means for reciprocating said impeller within said tube.
15. 2. A conveyor as defined in claim 1 wherein said tube includes means forming generally radially extending and longitudinally spaced internal circumferential surfaces to aid in resisting movement of the material with said impeller during the return stroke of said impeller.
20. 3. A conveyor as defined in claim 2 wherein said tube comprises a spirally wound interfitting element defining said internal surfaces.
25. 4. A conveyor as defined in claim 1 wherein said means for reciprocating said impeller comprises at least one annular solenoid coil mounted on said tube, and said flexible impeller includes means forming a magnetic armature located within said tube in close proximity with said coil.
30. 5. A conveyor as defined in claim 1 wherein said impeller includes a plurality of longitudinally arranged propelling elements each having a generally radial propelling surface adjoining a generally tapered surface, and flexible means connecting said elements.
35. 6. A conveyor as defined in claim 5 wherein said flexible means connecting said elements comprises a longitudinally extending flexible rod extending generally through the center portion of each said element.
40. 7. A conveyor as defined in claim 5 wherein each said element has a generally semispherical configuration with an annular said propelling surface.
45. 8. A conveyor as defined in claim 1 in combination with a supply container for receiving said flocking material, said tube having an inlet end and an outlet end, means connecting said inlet to said container, means for directing material from said container into said inlet, and means connected to said outlet for dispensing the material conveyed through said tube.

UNITED STATES PATENT OFFICE
CERTIFICATE OF CORRECTION

Patent No. 3,597,126 Dated August 3, 1971
Inventor(s) Carl L. Brumbaugh

It is certified that error appears in the above-identified patent and that said Letters Patent are hereby corrected as shown below:

On the cover sheet [56], in the References Cited, "2,713,173" should read -- 2,731,173 --. Column 2, line 65, "S thereby" should read -- within --.

Signed and sealed this 12th day of September 1972.
